UNITED STATES PATENT OFFICE.

MARY EVELYN BENDELARI, OF NEW YORK, N. Y.

CLOSURE FOR SHOE UPPERS.

Application filed November 23, 1926. Serial No. 150,328.

This invention relates to improvements in the closures of apparel, and more particularly to the type especially adapted for shoes.

5 One of the essential objects in view is the increasing of ease and efficiency of operation while enhancing the beauty and artistic finish of a closure for shoes and the like.

A more detailed object is the arrangement 10 of groups of securing means in such relation to each other that each individual part of each group finds bearing and support in engagement with individual parts of the other group.

15 Another object is the provision of a closure of such an adjustable character as to readily adapt it to the complete comfort and ease of the wearer across the instep or other part of the foot covered by the closure.

20 With these and other objects in view as will in part hereinafter become apparent and in part be stated, the invention comprises certain novel constructions, combinations and arrangements of parts as subsequently specified and claimed.

In the accompanying drawings,—

Figure 1 is a perspective view of a shoe embodying the features of the present invention.

30 Figure 2 is a plan view of the closure structure and surrounding parts detached and in a flattened condition, the closure being in its closed position.

Figure 3 is a view similar to Figure 2 35 with the closure somewhat relaxed.

Figure 4 is a view similar to Figure 1 of a slightly modified embodiment.

Figure 5 is a view similar to Figure 2 of the embodiment seen in Figure 4.

40 Figure 6 is a view similar to Figure 1 of a further embodiment.

Figure 7 is a view similar to Figure 2 of a still further embodiment, the fragments of the body of the shoe being omitted.

45 Figure 8 is a view similar to Figure 7 of a further embodiment of the invention.

Figure 9 is a detailed section taken on the plane indicated by line 9—9 of Figure 8.

Referring to the drawings by numerals, 50 1 indicates generally the body of a shoe inclusive of the several parts into which the upper of a shoe is commonly divided by those familiar with the shoe industry. The upper or body 1 thus includes the counter or quarter 2, the vamp 3, and the upper closure whether the closure be located

immediately across the instep as shown or otherwise. Said closure is made up of a series of lacings 4, 4, and a similar series of lacings 5, 5, crossing the lacings 4 60 obliquely and interlaced therewith substantially after the form of a basket weave. The said lacings 4 and 5 may be formed from and integral with the body of the shoe or may be otherwise constructed, and will 65 usually assume the character of straps, so that the word "strap" will be utilized hereinafter in referring to these parts, although, of course, a ribbon, strand, or strip of any kind suitable for the purpose may be utilized and should be considered in the interpretation of the appended claims as the full mechanical equivalent of the strap or straps 70 therein named.

As seen in Figures 1, 2, and 3 of the drawings, the straps 4 and 5 are formed integral with the material of the body of the shoe, and the straps of each series or group respectfully terminate at their free ends in an anchorage piece or tab 6, which may be 75 an appropriate strip of leather, or other material, corresponding to the material of the straps 4 secured to the respective straps and provided with an eye 7 adapted to engage an appropriate button or other 80 fastener 8 carried by the body of the shoe. The button 8, in each instance, is adjusted to the comfort of the wearer, and the closure formed of the straps 4 may be, accordingly, varied as required. The interlacing of the 85 straps 4 and 5 is preferably carried out, as seen in detail in Figures 2 and 3, but other interlacings may be utilized as found desirable, one essential advantage of this arrangement being the guiding and retention of the 90 straps in their functioning. Another advantage arises from the fact that the several interlaced straps afford relative support for each other, and proportionally prevent curling or other unsightly or undesirable dislocation or derangement. The loosening of the closure and the tightening 95 thereof are accomplished with a maximum of ease and minimum of time. A single point of purchase for the fastening of one group 100 of straps is all that is required, and the principle of operation will be the same even though a greater or less number of straps be employed than illustrated and even though the extent of the opening in the 110 upper be increased to correspond to a high-top shoe or even a boot.

In use, the closure assumes the position seen in Figures 1 and 2, but, when it becomes desirable to remove the shoe, the buttons 8 are released through the eyes 7, and groups 5 of straps comprising the closure are relaxed to the position seen in Figure 3. Obviously, a greater relative movement of the straps may be accomplished if further opening is needed for ease of removal and introduction 10 of the foot. It will be observed that in moving to the relaxed position, the straps of each group move as a group longitudinally of the straps of the other group, each strap of each group moving edgewise and playing 15 in and out according to the interlacing or weave of the closure.

Obviously, the buttons 8 will be located in each particular instance according to the need and comfort of the individual wearer 20 and will be so placed that, when the tabs 6 engage the buttons, the groups of straps 4 and 5 will snugly, neatly, and comfortably enclose the engaged part of the foot of the wearer, the instep in the instance shown in 25 Figure 1.

In Figures 4 and 5, I have illustrated a further embodiment of the invention in which the same principle is utilized, differing chiefly from the embodiment seen in 30 Figure 1 in that the oblique crossing of the upper closure of Figure 1 is arranged for the several straps to extend on an upward incline while the free ends of the closure structure seen in Figures 4 and 5 extend generally 35 downward. In accomplishing this result, the body 1' of the shoe is formed with a series of straps 4' interlaced with cooperating straps 5', each group of straps terminating in an attaching strip or tab 6' provided with an eye 7' designed to engage the retaining button 8' arranged at an appropriate point on the body of the shoe. As clearly seen in Figures 4 and 5, the two groups of straps have their movable or free ends 40 extending generally in a downward direction, so that, in operation, when the securing tabs 6' are pulled for drawing the closure tight, the pressure is exerted downward about the sides of the shoe body in the general direction 45 of the length of the straps as distinguished from a pull upward and in a rearward direction when securing the tabs 6 of the structure seen in Figure 1.

In Figure 6 is illustrated a further embodiment in which the opening of the upper or shoe body 1'' is closed substantially after the manner seen in Figure 4, but differing therefrom in that the several straps 4'' and 5'' are attached at 2'' at the rear of the shoe body and brought forward therefrom across the foot of the wearer just above the instep of the wearer instead of springing from the middle portion of the body of the shoe. In the embodiment seen in Figure 6, the opening 55 in the upper is theoretical only, because

the body of the shoe 1'' is finished like a pump and the interlacing straps 4'' and 5'' serve as a closure in the sense of affording anchorage to the body of the shoe near the rear thereof and at the sides where the buttons 8'' are engaged by the eyes 7'' of the attaching tabs 6'' of the respective straps 4'' and 5''. When the tabs 6'' are released from buttons 8'', the movement of the straps relative to each other is substantially the same 75 as that heretofore stated, save that the interlacing is single only, and, therefore, not of the complete form of basket weave. By "single" in referring to the lacing is meant that the crossing of any one strap of any one group relative to the other group is accomplished without actual weaving. For example, the uppermost strap 4'' merely overlies all of the straps 5'', the intermediate strap 4'' underlies the uppermost strap 5'' 85 and overlies the other two straps 5'', and the lowermost strap 4'' underlies the upper and intermediate straps 5'' and overlies the lowest strap 5''.

In Figure 8 is seen a still further modified embodiment of closure, the closure alone being illustrated. In this figure, the straps 4^b and 5^b are interlaced after the manner of the straps 4 and 5, except that the terminal tabs 7^b of the straps 4^b and 5^b are at the lower ends of the straps and are designed to be attached to the body of the shoe at the opposite sides of the opening in the upper. By this arrangement of the tabs 7^b, the 90 opposite ends of the straps from those engaging the tabs are preferably left integral with that which constitutes the fastening piece 10. The said fastening piece 10 may be detachably anchored to the body of the shoe in any appropriate and well known or acceptable manner, as, for example, by the provision of an eye or eyes 11 adapted to engage appropriately located buttons carried by the body of the shoe. In the closing and releasing of the securing means, as seen in Figure 7, the movement of the straps relative to each other is substantially the same as the operation of the parts as seen in Figure 1.

In Figure 8 is illustrated a further embodiment in which 1^c indicates the body of the shoe having a closure made up of the groups of straps 4^c and 5^c extending from and formed integral with the material of the body and terminating in the attaching tabs 6^c having the eyes 7^c adapted to engage the securing buttons or fasteners 8^c. The form of interlacing of the straps 4^c and 5^c is the same as interlacing of the straps 4^a and 5^a, the attaching ends of the straps, however, uniting in a single tab instead of being independent as are the straps 4^a and 5^a. The straps 4^c and 5^c also are distinguished from straps 4^a and 5^a in being straight instead of arcuate. Otherwise, the structure is mechanically the same, except that, for pur- 115 120 125 130

poses of finish and for protection of the straps, the material of the body 1^c is extended at each side of the opening 13 upwardly to form cover strips 12, 12, overlying the 5 respective groups of straps 4^c and 5^c. The overlying or protecting strips or plates 12, 12, may terminate, as preferred, but are preferably extended downward inside of the groups of straps 4^c and 5^c, and appropriately attached to the body 1^c, so that each part 10 12 is, in fact a complete loop through which the respective group 4^c or 5^c is passed. As the operation is substantially identical with that of the structure seen in Figure 6, the 15 same will be obvious, and it will be noted that the covering strips or plates 12 are free to flex, as indicated in dotted lines, when the closure straps are released.

It will of course, be understood that the 20 several straps may be formed integral or stitched to the respective parts of the shoe body, and the shoe body may be constructed in any conventional or improved form while incorporating the invention herein disclosed.

25 What is claimed is:

1. The combination, with a shoe upper having an opening, of a group of straps extending from one side of the opening across the same, and a similar group of straps extending from the other side of the opening across the opening and across the first-mentioned straps and lying in face contact therewith, each strap of each group being interwoven with the straps of the other 35 group and lying across at least two of such straps and being free and adapted for edgewise sliding movement relative to said other group.

2. A closure for a shoe upper comprising 40 a plurality of groups of straps crossing each other, and means for simultaneously shifting the straps relative to each other, each strap of each group being interwoven with the straps of the other group and lying across at least 45 two of such straps and being free and adapted for independent movement relative to said other group.

3. A closure for a shoe upper comprising

a plurality of groups of straps crossing each other, the individual straps of one group being laced through and relative to and woven across a plurality of the straps of the other group while leaving the groups free for longitudinal movement. 50

4. A closure for a shoe upper comprising a 55 plurality of groups of straps crossing each other and interlaced into the form substantially of a basket weave, each group being movable relative to the other for varying the area of the opening of the shoe upper. 60

5. The combination, with a shoe upper having an opening, of a group of straps connected at one side of the upper, and a second group of similar straps connected at the other side of the upper and crossing the first 65 group at said opening, the groups being interwoven and relatively shiftable for varying the effective area of the opening.

6. The combination, with the body of an article of apparel, of a closure therefor comprising a plurality of groups of straps crossing and interwoven with each other in condition for relative sliding movement, each individual strap lying in face contact with a plurality of other straps at the places 75 of crossing the same, and each strap being free and adapted for edgewise and longitudinal sliding movement relative to the other straps with which it is interwoven.

7. A closure for a shoe upper comprising 80 a group of straps adapted to extend from one side of an upper opening, a similar group adapted to extend from the opposite side of said opening and having each strap of the second group arranged to lie across the 85 first-mentioned group and interwoven with at least two of the straps of the first-mentioned group while left free for edgewise and longitudinal movement independently of the straps in which it is interwoven, means 90 connecting the free ends of one group, and means connecting the free ends of the other group for causing each group to move as a unit.

In testimony whereof I affix my signature.
MARY EVELYN BENDELARI.
